UNITED STATES PATENT OFFICE.

HENRY ROBERT HOWARD CLAYTON AND OSBOURNE JOHN ROSE, OF HOBART,
TASMANIA, AUSTRALIA.

MACHINE FOR BREAKING UP TOFFEE AND OTHER LIKE MATERIALS.

1,335,937.

Specification of Letters Patent.

Patented Apr. 6, 1920.

Application filed September 8, 1919. Serial No. 322,538.

To all whom it may concern:

Be it known that we, HENRY ROBERT HOWARD CLAYTON, engineer, and OSBOURNE JOHN ROSE, manufacturer, both residents 5 of 116 Collins street, Hobart, in the State of Tasmania, Commonwealth of Australia, subjects of the King of Great Britain, have invented a certain new and useful Machine for Breaking Up Toffee and other like Materials, of which the following is a specification.

This invention relates to machines for breaking up toffee and the like and has for its object the parting of the material into 15 convenient eatable sized pieces in an easy, clean and economical manner.

According to this invention jaws are provided one of the parts of which is adapted to an up and down motion to articulate with 20 the other part that is fixed and positioned about level with or slightly below a hinged feed plate susceptible to an up and down movement as the machine operates to part or break up the material. The feed plate 25 may be constructed with a guard and as the material is broken it will fall into scales or other receptacles placed beneath, from whence it is filled into bags or other containers for delivery.

30 In the accompanying drawings:—

Figure 1 is a side elevation of the machine and

Fig. 2 a perspective view of the same showing the flexible feed plate and guard.

35 Upon the bed plate 3 a pillar 4 supports the end of the member 5 of the breaking device, the other or fixed member 6 being held in the bracket 7 that is also upon the bed plate. In the bracket is a spindle 8 on 40 which is the fly wheel 9 and the spur wheel 10 that meshes with the toothed wheel 11 mounted on the bracket 7.

The wheel 11 is positioned about midway 45 of the length of the jaw member 5 which latter is provided with a stud and roller 12. The wheel is hollow in the center and is fitted with a cam member 13 upon which the part 12 rolls as the wheel rotates, the wheel being mounted in the machine in such a way 50 that while it revolves the roller will be left undisturbed upon the cam surface. The fixed member 6 is socketed in the base of the bracket 7 and is retained in place by the pin or spindle 14. The toothed wheels 10

and 11 receive motion from the wheel 9 on 55 spindle 8 and as 11 revolves the jaw member 5 will be given a reciprocating motion about its support on 4 when its movement will be sufficient to bring it almost into contact with the fixed part 6. A coiled spring 15 60 on the bed plate 3 bears upon the under side of the part 5 and serves to return it to the normal position, thereby opening the jaws.

Hingedly mounted on the spindle 14 is a feed plate 16 that is so fashioned that its inner 65 edge should be slightly above the point of the fixed part 6 of the jaws. The plate may be also provided with a guard 17 and a coiled spring 18 bears upon its underside for the purposes hereafter to be explained. 70 The material to be parted is placed on the plate 16 and fed thereon into the jaws of the breaker; as the piece is engaged by the part 5, the downward movement thereof will cause the plate to be depressed thereby 75 permitting the material to be gripped by and broken in the jaws. As the pieces are parted some will fall over the plate into scales or some other convenient receptacle placed immediately below, thus saving all the fragments and avoiding waste. As each piece is 80 broken off the spring will react to raise the plate so that the block of material may be fed forward to come between the jaws ready to receive the pressure of the upper member 85 as it again descends. The position of one part of the jaw below the surface of the feed plate and the pivotal mounting of the same upon the spindle 14 thus facilitates the easy and continuous feeding of the slab of hard 90 bake, toffee or other material between the jaws, large quantities of which can be parted easily and expeditiously upon the counter of a store or other convenient place.

In operation, the appliance is placed in 95 position with the breakers over, preferably, the weighing scales and the piece of material to be parted is put on the feed plate 16. On the handle 9 being turned the wheel 11 and cam 13 will rotate in contact with the 100 roller 12 on the bar 5, the cam imparting to the same the reciprocating movements, assisted by the spring 15. Instead of the construction of cam as shown same may be a cam race containing the roller 12 and in 105 such case the buffer spring 15 need not be used.

Having now described our invention what

we claim as new and desire to secure by Letters Patent is:—

1. In a machine of the kind indicated, a jaw composed of a fixed member and a movable part, a cam device revolving in the machine connected with and reciprocating said movable part and a feed plate susceptible to an up and down motion, the feeding surface of which is normally slightly above the cutting edge of the said fixed member.
2. In a machine of the kind indicated, a jaw composed of a fixed member and a movable part, a cam device revolving in the machine connected with and reciprocating said movable part, a feed plate susceptible to an up and down motion, the feeding surface of which is normally slightly above the cutting edge of the said fixed member and a guard to the feed plate with an opening between the plate edge and the guard.
3. In a machine of the kind indicated, a jaw comprising a pivotally mounted reciprocating member and a fixed member, a cam wheel connected with the movable member, a flexibly mounted feed plate the surface of which is slightly above the edge of the

fixed member of the jaw and means for revolving the cam wheel in the machine.

4. In a machine of the kind indicated, a jaw comprising a pivotally mounted reciprocating member and a fixed member, a cam wheel connected with the movable member, a compression spring bearing on said member, a flexibly mounted feed plate and a guard thereto, the surface of said plate being just above the cutting edge of the fixed jaw member and means for revolving the cam wheel in the machine.

5. In a machine of the kind indicated, a jaw comprising a reciprocating member and a fixed member, a cam wheel connected with the movable member, a compression spring bearing on and below said movable member, a pivotally mounted feed plate the surface of which is slightly above the cutting edge of the fixed member of the jaw, a compression spring below the feed plate and means for revolving the cam wheel in the machine.

In witness whereof we affix our signatures.

HENRY ROBERT HOWARD CLAYTON.
OSBOURNE JOHN ROSE.
